(57) **CLAIM**

The ornamental design for a camera, as shown and described.

DESCRIPTION

FIG. 1 is a front bottom perspective view of a camera showing our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is a cross-sectional view taken along line 8-8 of FIG. 2;

FIG. 9 is an enlarged portion view taken from encircled portion labeled, “FIG. 9” in FIG. 8; and,

FIG. 10 is a front bottom perspective view of the camera in FIGS. 1-9 shown in a use condition with the cover in an alternate position.

The dashed-dot lines form the boundary of the enlarged portion views in FIGS. 8 and 9 and form no part of the claimed design. The even broken lines shown in the drawings are included for the purpose of illustrating portions of the camera that form no part of the claimed design.
